UNITED STATES PATENT OFFICE

2,040,013

TUBE CAP

Richard D. Moore, Birmingham, Ala.

Application November 9, 1934, Serial No. 752,317

1 Claim. (Cl. 221—60)

This invention relates to caps for collapsible tubes and its general object is to provide a closure in the form of a cap for automatically dispensing the contents of a tube, in that when pressure is applied to the tube the closure automatically opens to allow the contents to be expelled therefrom and when the pressure is relieved it closes; therefore, the contents are retained free from exposure and in a clean and sanitary condition, when the tube is not in use.

A further object of the invention is to provide a closure that is automatic in its action, yet can be held and retained closed even though pressure is applied to the tube; therefore, fear of leakage or waste of the contents is eliminated, when the tube is packed for shipping or the like.

Another object of the invention is to provide a closure cap of the character set forth, that allows for the complete removal of the contents of the tube, is simple in construction, inexpensive to manufacture, can be applied to the necks of all tubes now in commercial use, and is extremely efficient in operation and service.

This invention also consists in certain other features of construction and in the combination and arrangement of the several parts, to be hereinafter fully described, illustrated in the accompanying drawing and specifically pointed out in the appended claim.

In describing my invention in detail, reference will be had to the accompanying drawing wherein like characters denote like or corresponding parts throughout the several views, and in which:

Figure 1 is a front elevation showing the application of my closure to a tube of the usual construction.

Figure 2 is a fragmentary view showing the closure in section and applied to a tube having a relatively large neck, with the parts of the closure in operative position.

Figure 3 is a top plan view of my closure.

Figure 4 is a fragmentary view showing the closure applied to a tube having a relatively small neck with an adapter for the latter.

Referring to the drawing in detail, the letter A indicates the body of the usual collapsible tube and the tube as shown in Figure 2 includes a relatively large neck B, while that shown in Figure 4 is provided with a relatively small neck C, in order to illustrate that my closure can be associated with collapsible tubes having necks of various sizes; and, notwithstanding the fact that the closure is of the same size in every respect, I may employ an adapter which, for

distinction, is indicated by the numeral 1. These adapters have threaded bores 2 extending centrally therethrough, and of course it will be understood that the bores of the adapters vary in diameter to fit various sizes of necks, to be 5 threadedly mounted thereon as clearly shown in Figure 4. The outer surfaces of the adapters are screw threaded to threadedly receive my closure.

The closure as shown is in the form of a cap 10 and includes a skirt 3 that provides the body therefor, and the skirt or body is interiorly threaded to be threadedly received on the neck B or on an adapter such as indicated by the reference numeral 1. The skirt is provided with an 15 outwardly rounded annular bead 4 that is serrated in order to facilitate the application and removal of the closure as will be apparent.

From the skirt 3 the closure is somewhat restricted to provide an upper hollow portion 5 that 20 has arranged laterally therein an opening in the form of a slot 6 and which communicates with the interior thereof so as to act as an outlet opening for dispensing the contents of the tube therefrom in a manner which will be pres- 25 ently apparent. The upper hollow portion is provided with a substantially dome shaped top 7 having a central opening extending therethrough for the purpose of receiving a plunger rod 8 for slidable movement therein and which 30 has a knob on its outer end to limit its inward movement, while its inner end is fixed to a plunger or piston 9, the latter being in the form of a concavo-convex disk of a size to fit the portion 5 for slidable movement therein. 35

Surrounding the plunger rod 8 for disposal between the piston 9 and the top 7 is a coil spring 10 which tends to move the piston 9 inwardly of the hollow portion 5 as shown in dotted lines in Figure 2, and the spring 10 is of the telescopic type, so that its coils fit within each other as shown, in order to take up minimum space. The piston 9 is arranged to control the outlet opening 6 and is normally disposed inwardly beyond 40 the opening as shown in dotted lines in Figure 2. However, when pressure is applied to the body A of the tube, the contents of the latter will be forced against the plunger or piston 9 and move the same against the pressure of the spring 10 45 to the full line position of Figure 2, or outwardly beyond the outlet opening, so as to allow the contents of the tube to pass through the latter in ribbon formation, as clearly shown in Figure 2. When the pressure is relieved, the coil spring will 50 55

move the plunger or piston 8 to its normal position.

The plunger rod 8 performs a dual function, namely, it acts to guide the plunger or piston 8 in its movement and it can be used to manually actuate the piston in the event it becomes necessary to do so. Again, the plunger rod performs another function, namely, to prevent the piston or plunger from being moved to open position in the event accidental pressure is applied to the body A of the tube when the latter is packed for shipping or the like, as it will be obvious that an obstruction can be disposed against the outer end of the plunger rod to prevent outward movement thereof, such as for instance a block or the like arranged within a container for the tube, or the top of the container can contact the outer end of the plunger as will be apparent, with the result that the contents of the tube will remain intact until it reaches the user.

It is thought from the foregoing description that the advantages and novel features of my invention will be readily apparent.

I desire it to be understood that I may make changes in the construction and in the combina-

tion and arrangement of the several parts, provided that such changes fall within the scope of the appended claim.

What I claim is:

A closure for a collapsible tube comprising a body having a dome shaped top and an internally threaded cylindrical bore adapted for detachable connection to the neck of the tube, a serrated bead exteriorly of the body, a restricted hollow portion formed on the body between the top and threaded portion and having a laterally disposed slot therein adjacent the top to provide an outlet opening, a concavo-convex disk-like plunger mounted for slideable movement in the hollow portion for controlling the opening, a plunger rod extending through the top and connected with the plunger to guide and manually actuate the same, a telescoping coil spring surrounding the plunger rod between said top and plunger and normally holding the plunger in closed position, said plunger being adapted to be acted upon by the contents of the tube when pressure is applied to the latter for moving the plunger to open position to eject the contents through the outlet opening.

RICHARD D. MOORE.
